CLAIM

The ornamental design for a cross bar extrusion, as shown and described.

DESCRIPTION

FIG. 1 is perspective view of the cross bar extrusion of the present design;

FIG. 2 is a left side view of the cross bar extrusion of the design of FIG. 1;

FIG. 3 is a right side view of the cross bar extrusion of the design of FIG. 1;

FIG. 4 is a left sectional view of the cross bar extrusion of the design of FIG. 1;

FIG. 5 is a right side sectional view of the cross bar extrusion of the design of FIG. 1;

FIG. 6 is a top view of the cross bar extrusion of the design of FIG. 1; and,

FIG. 7 is a bottom view of the cross bar extrusion of the design of FIG. 1.

The broken lines illustrate portions of the cross bar extrusion that form no part of the claimed design.

1 Claim, 4 Drawing Sheets
